UNITED STATES PATENT OFFICE.

PENROSE R. HOOPES, OF HARTFORD, CONNECTICUT, ASSIGNOR TO THE NEW ENGLAND ENAMELING COMPANY, INC., OF MIDDLETOWN, CONNECTICUT, A CORPORATION OF CONNECTICUT.

DESIGN FOR A DISPENSING-MACHINE CASE.

Application filed May 3, 1926. Serial No. 17,538. Term of patent 14 years.

To all whom it may concern:

Be it known that I, PENROSE R. HOOPES, a citizen of the United States, and a resident of Hartford, in the county of Hartford and State of Connecticut, have invented a new, original, and ornamental Design for Dispensing-Machine Case, of which the following is a specification, reference being had to the accompanying drawing, forming part thereof.

The figure is a perspective view of a dispensing machine case, showing my new design.

I claim:

The ornamental design for a dispensing machine case, as shown.

PENROSE R. HOOPES.
